SEISMOGRAPHIC PROSPECTING

Lacoste G. Ellis, Beaumont, Tex., assignor to Sun
Oil Company, Philadelphia, Pa., a corporation
of New Jersey

Application March 25, 1949; Serial No. 83,363

1 Claim. (Cl. 181—53)

1

This invention relates to seismographic prospecting and has particular reference to so-called reflection shooting. In ordinary reflection shooting a shot is fired either on the surface of the earth or within a relatively shallow shot hole which, considering the depth of the reflecting horizons of interest, effectively locates the shot at the surface. Detectors are also provided at the surface or adjacent to the surface in shallow holes; the detectors being arranged in various arrays which are calculated to give the most informative results. Such practices, however, have the disadvantage that in the event of deep reflections the point of reflection is so far removed from both the shot point and the detector that there is, in cases of complex structure, considerable doubt of the exact point of reflection. Furthermore, when the structure is complicated it is difficult to understand and picture geometrically the travel paths of the waves and, accordingly, there are introduced corresponding uncertainties in the interpretation of the structural conditions.

In accordance with the present invention the difficulties indicated are, to a major extent, avoided by accomplishing shooting in wells which are to be abandoned either because they have not produced or because their production has ceased to be of sufficient quantity to warrant their maintenance. By the use of the present method such wells may be effectively utilized to secure further information concerning the conditions existing in the adjacent field. In brief, in accordance with the invention an array of detectors is provided at or adjacent to the surface of the ground and a series of shots are fired within the well ordinarily starting at the greatest depth and progressing up the hole so that even if destruction occurs in the vicinity of and below the shot points a complete series of shots may be fired. The general objects of the invention will be apparent from the foregoing and details thereof will become clearer from consideration of procedures as outlined below in conjunction with the accompanying drawing in which Figures 1 and 2 illustrate diagrammatically generally vertical sections through the earth showing the fashions in which shooting is effected and the nature of the results attained thereby.

Referring to Figure 1, there is illustrated therein a well 2 which may be considered a well about to be abandoned. In general, such a well will have been surveyed so that its position at any given depth will be known to a considerable degree of accuracy and, furthermore, there will be known, as the result of coring or logging, the locations of

the strata penetrated by the well. With this knowledge it will be evident that explosive charges may be located within the well at various known positions not only as to coordinates with respect to the mouth of the well but also with respect to the various strata which have been penetrated. In particular, shot points may be located in the well between particular known interfaces from which reflections may be caused to occur.

10 There is indicated at 4 the weathered layer adjacent to the surface of the earth above which or in which detectors may be located. At 6, 8, 10, 12, 14 and 16 there are indicated interfaces between the strata which, in the course of ordinary reflection shooting, would constitute reflecting horizons. For simplicity, of course, the number of these is shown considerably less than would be usual in the case of an actual situation. The bottom of the hole is illustrated at 18 within the stratum between the interfaces 14 and 16.

Detectors may be arranged at the surface in any desired arrays, for example radiating from the mouth of the hole as indicated at 29 or surrounding the mouth of the hole in arcs or other fashions as indicated at 28'. These detectors will be of the type generally used for reflection shooting and, as in ordinary reflection shooting, will be connected to recorders of conventional types. Inasmuch as the particular detecting apparatus used may be conventional it need not be detailed herein. It may comprise, for example, filtering arrangements for the purpose of accentuating reflections, automatic volume controls, means for determining the instant of firing, etc.

35 In accordance with the invention, with a given array of detectors, shots are fired, for example, as indicated at S₁, S₂, S₃ and S₄ in succession, the shots being desirably located between different pairs of reflecting horizons. Considering specifically Figure 1, it will be noted that the first shot point S₁ is located at or near the bottom of the well between the horizons 14 and 16. In order to avoid undue complication in the figure there are illustrated only the rays reaching the second

40 and sixth detectors 20 located at one side of the mouth of the hole. The direct rays from the shot point S₁ are indicated at D₁ and D'₁ and reflected rays from the horizon 16 are indicated at R₁₀ and R'₁₀. A consideration of Figure 1 will reveal that a shot at the point S₁, which shot will be fired through connections to the surface which are not shown, may produce the indicated reflections from the horizon 16 and possibly from deeper horizons but that reflections will not occur 45 from horizons such as 14, 12, etc. above the shot

point S_1 , though some refraction of the rays may occur at these upper horizons. At any rate, it will be evident that the travel times of the reflections, for example, from the horizon 16, will be only slightly greater, in general, than the travel times of the direct rays from this same shot point and, consequently, the reflections from the horizon 16 may be rather easily detected on the seismograph record in contrast with the reflections from deeper horizons. Furthermore, since the shot point S_1 is accurately known it will be evident that the seismographic record may be easily interpreted to provide an accurate picture of the contour of the horizon 16. This determination of the contour of horizon 16 may be made much more accurately than if the shot point was located at the surface and the same is true of the contours of lower horizons in view of the fact that the shot point will be much closer thereto than a shot point at the surface. The travel times of the rays reflected by such lower horizons will, of course, be considerably less than if the shot point was at the surface. Furthermore, there are eliminated reflections from higher horizons so that interferences by reflections from them will be 10 eliminated from the record.

The firing of the shot at S_1 will, of course, generally destroy the portion of the hole in its vicinity but since succeeding shots are fired thereabove there is no interference with the possibility of providing such shots.

The next shot may be fired at the point S_2 above the next higher horizon 14 or above some still higher horizon since these may be rather closely spaced. It will be noted that the shot fired at S_2 will produce not only reflections R_{20} and R'_{20} from the horizon 16 but also reflections R_{21} and R'_{21} from the horizon 14. This means that the passage from below to above the horizon 14 for the new shot point will produce distinctly new reflections in the record which were not present in the record formed by the shot at S_1 . These new reflections may be easily identified. Of course, if several reflecting horizons existed between the two successive shot points a corresponding number of new reflections would appear in the record made by each of the detectors. Following this, new shots may be fired at the shot points S_3 , S_4 , etc.

It will be evident that the records thus produced not only show different numbers of reflections but will be more indicative of the nature of the horizons in the general vicinity of the well than records produced by shots at the surface. Local slopes, for example, can be much more readily determined. As is usual, of course, interpretations are based on the delays of the reflections from the instant of firing of the shot.

Another situation which may arise is that illustrated in Figure 2 in which the well 22 is illustrated as passing near a fault F. Shot points are indicated at S_5 , S_6 and S_7 . While considerations as above described will also exist, i. e., the appearance of new reflections as the shot point rises above reflecting horizons, there will also exist situations such as that exemplified by reflections from the horizon 24, interrupted by the fault, due to a shot at the shot point S_7 . Various reflections are indicated at R_3 , R_4 and R_5 . It will be noted that the reflections R_3 and R_4 are from portions of the horizon to the left of the fault. The reflection

5 R_5 , on the other hand, is from a portion of the horizon to the right of the fault and the relative transit times of the reflections R_4 and R_5 will be related to the fact that the horizon level is displaced by reason of the fault. Intermediate reflections between R_4 and R_5 will also be informative and, in fact, as will be apparent, one or more of these might not appear at all. Such an absence of reflections may be interpreted in terms of an accurate location of the surface of the fault.

15 The discussions of the types of reflections produced have, of course, been somewhat idealized since, in general, considerably more complication is involved in interpretation of results than those indicated; but those skilled in this art are accustomed to take into account the geometrical complications which may appear and are able to provide complete analyses of the records which are produced. As indicated, the advantage of the present invention lies in the fact that the reflections are from points on the horizons relatively close to the shot points and analysis is considerably simplified with more accurate evaluation of the significance of the various records. It may be noted that attempts to reverse the directions of the rays will not be nearly as satisfactory in view of the fact that many more shots would be required to secure the same results and those detectors located in the hole would receive their signals from various directions so that there could not be gained the usual advantages of using the detectors commonly used in reflection shooting which have sensitivity characteristics which are directional.

20 35 As a result of the invention deep reflecting horizons may be mapped to a high degree of accuracy when their depths are comparable with the depths of successive shot points.

30 40 What I claim and desire to protect by Letters Patent is:

A method of reflection shooting comprising providing an array of detectors, adapted to receive reflections from deep strata, adjacent to the surface of the earth at different distances from the 45 top of a bore hole penetrating deep reflecting horizons the orientation of which is sought, and firing successively within said bore hole a series of shots, one of said shots being fired below one of said deep reflecting horizons, and a subsequent 50 shot being fired above said horizon and below the next higher reflecting horizon, so that in the case of said second shot reflections to said detectors will occur from said first mentioned horizon, from which no direct reflection to said detectors will occur due to said first mentioned shot, the reflections 55 from said horizons being received by said detectors substantially later than direct waves from said shots.
